UNITED STATES PATENT OFFICE.

BERNARD NEWMAN AND OLIVER WICKHAM, OF GRAYS, ENGLAND.

FLOAT FOR USE IN STORAGE TANKS FOR VOLATILE LIQUIDS.

Application filed November 29, 1926, Serial No. 151,502, and in Great Britain February 27, 1926.

This invention relates to means for storing and protecting liquids, and it has for object improvements by which certain advantages shall be obtained.

5 The sealing of a liquid can be efficaciously effected by forming thereon a film of lighter liquid which film will adapt itself to all irregularities of the containing vessel, but with volatile liquids of low specific gravity, such as motor spirit, a difficulty arises in that they will not support any known liquid without becoming contaminated therewith.

10 According to the present invention means for storing and protecting liquids comprises a tank having a plurality of floats to cover the surface of the liquid.

15 The floats may be of a similar shape in plan, for example hexagonal, square, triangular, or circular, and by employing a larger number than are required to cover the surface of the liquid a wedging action is produced between the floats at the surface of the liquid.

20 The floats may contain fire extinguishing material. Thus they may be filled with an inert gas or may have an aperture in the upper surface and contain materials which on subjection to heat will be ejected from the floats and produce a fire extinguishing 25 blanket.

25 A form of float suitable for the purpose of the invention is of hexagonal, square or triangular shape in plan and at the plane of immersion, and has a depending portion of 30 pyramidal form, which term includes conical form.

35 The invention will now be described with reference to the accompanying drawings wherein:—

40 Fig. 1 shows a sectional side elevation of a tank embodying the invention and of the type usually employed for storing volatile liquids, such as motor spirit;

45 Fig. 2 shows a similar view to Fig. 1 but with the tank filled with liquid;

50 Fig. 3 is a similar view more or less diagrammatical and on a smaller scale, of a modified arrangement;

Fig. 4 is a similar view to Fig. 3 of a further modified arrangement;

55 Fig. 5 shows an elevation of one form of float;

Fig. 6 a plan thereof, and

Fig. 7 sectional elevation of a modified form of float.

Fig. 8, is a vertical section, more or less diagrammatical, through one of the modified forms of float of Figs. 3 and 4.

Referring to Fig. 1, 1 is a tank of the type usually employed for storing motor spirit; 60 2 is a pipe of usual form angularly adjustable about its lower end 3, and through which the liquid is withdrawn from the tank. This pipe 2 is sometimes employed as the filling means for the tank. 4 is a usual 65 form of foot valve inlet. The tank is indicated as partially filled with liquid and the surface of the latter covered by a number of floats 6 of the kind illustrated in Fig. 7. Each float is hexagonal in plan, has a 70 domed top 7 and a depending portion 8 of pyramidal form, and is weighted to maintain it in position in the liquid. The domed top 7 is joined to the pyramidal depending portion 8 by an intermediate part which comprises a part 9 having a vertical wall, and a second part 10 also having a vertical wall, said parts being separated by two parallel 75 grooves 11. It is also preferable to arrange the part 9 to be set back slightly beyond the 80 part 10. Some or all of the floats have an aperture 19 in their upper surfaces and a tube 20 extending therefrom into fire extinguishing liquid 21 contained in the bottom of the float. The aperture 19 is covered 85 by a fusible plug 22, see Fig. 7. The floats nest together at the surface of the liquid and cover it more or less completely. The number of floats placed in a tank is preferably 90 more than sufficient to cover the surface of the liquid therein so that one or more are forced out of the liquid as shown at 12 in Fig. 1 and a wedging action is produced 95 which maintains the floats in close contact with each other and the sides of the tank. The floats are so constructed that they are immersed to a point on or below the part 10, and the grooves 11 prevent the liquid creeping up over their upper surfaces.

In Fig. 2 the tank is shown filled with liquid and it illustrates how the floats will nest round an obstruction such as a roof support 13, a bracket 15, or a dip or gauge pipe 14. Should the liquid in the tank become ignited the heat will cause the fusible plug to melt 105 and the fire extinguishing material 21 to be ejected from the float and flow over the surface of the liquid whereby the fire will be extinguished.

Referring to Fig. 3 the floats 6' (see Fig. 110

8) illustrated are spherical and means comprising a metal screen 16 is provided to localize the floats when the tank is empty or nearly empty, to keep them free from, for example, the manhole 17.

Fig. 4 illustrates a modified form of tank in which the roof is supported by columns 18 and indicates how the floats will nest round such columns. In this figure sufficient floats 6' of spherical form are shown to produce a double layer, the floats in the upper layer covering the spaces between the floats in the lower layer so that the surface of the liquid is practically completely covered.

In use the floats rise and fall with the liquid in the tank and maintain a seal under all normal conditions. The tank may be of any form but means such as screens, should be provided to prevent the floats from entering outlets, draw offs, and the like. The floats may be of glass, metal or other material, and the required number having been introduced into a tank they will require no further attention. It will be understood that a large floating mass may be employed in conjunction with a number of smaller floats.

What we claim is:—

- 30 1. A float for use with a plurality of others to cover the surface of liquid in a tank, said float having a depending portion of pyramidal form and a groove around its side wall above the plane of immersion.
- 35 2. A float for use with a plurality of others to cover the surface of liquid in a tank, said float having a weighted depending portion of pyramidal form and a groove around its side wall above the plane of immersion.
- 40 3. A float for use with a plurality of others to cover the surface of liquid in a tank, said float having a depending portion of pyramidal form, a vertical wall between the depending portion and the top of the float, and said vertical wall having a groove therearound above the plane of immersion.
- 45 4. A float for use with a plurality of others to cover the surface of liquid in a tank, said float having a depending portion of pyramidal form, a vertical wall between the depending portion and the top of the float, and said vertical wall having a groove therearound above the plane of immersion.
- 50 5. A float for use with a plurality of others to cover the surface of liquid in a tank, having a depending portion of pyramidal form, said float chambered, and fire extinguishing material in said chamber.
- 55 6. A float for use with a plurality of others to cover the surface of liquid in a tank, having a depending portion of pyramidal form, said float chambered, fire extinguishing material in said float chamber, the upper

surface of the float having an aperture therein, and a tube extending from said aperture to said fire extinguishing material.

7. A float for use with a plurality of others to cover the surface of a liquid in a tank, having a depending portion of pyramidal form, the side wall of the float having a groove therearound above the plane of immersion, the float chambered, fire extinguishing material in the float chamber, the upper surface of the float having an aperture therein, and a tube extending from said aperture in the upper surface to the fire extinguishing material in said float chamber.

8. A float for use with a plurality of others to cover the surface of liquid in a tank, having a depending portion of pyramidal form, said float chambered, fire extinguishing material in said float chamber, the upper surface of said float having an aperture therein, a tube extending from said aperture to the fire extinguishing material, and fusible means closing said aperture.

9. A float for use with a plurality of others to cover the surface of liquid in a tank, having a depending portion of pyramidal form, the side wall of the float having a groove therearound above the plane of immersion, the upper surface of the float having an aperture therein, said float chambered, fire extinguishing material in the float chamber, a tube from the aperture to the fire extinguishing material, and a fusible member closing said aperture.

10. A float for use with a plurality of others to cover the surface of liquid in a tank, having a depending portion of pyramidal form, a vertical wall between the depending portion and the top of the float, the vertical wall having parallel grooves therearound above the plane of immersion, the top of the float having an aperture therein, the float chambered, fire extinguishing material in the float chamber, a tube extending from the aperture to the fire extinguishing material, and a fusible member closing said aperture.

11. A float for use with a plurality of others to cover the surface of liquid in a tank, having a depending portion of pyramidal form, said float chambered, fire extinguishing material in the float chamber, a vertical wall between the depending portion and the top of the float, said wall provided with a groove therearound above the plane of immersion and that portion of the wall above the groove set back from that portion of the wall below said groove, the top surface of the float having an aperture therethrough, a tube extending from the aperture to said fire extinguishing material, and a fusible member closing said aperture.

12. A float for use with a plurality of others to cover the surface of liquid in a tank, said float having a chamber therein

adapted to contain fire extinguishing material, the float provided with an aperture therethrough and being constructed and arranged to normally maintain the aperture 5 above the plane of immersion of said float, a tube from the aperture to said float chamber, and fusible means normally closing said aperture and tube.

13. A float for use with a plurality of 10 others to cover the surface of liquid in a tank, said float provided with a circumferential groove and being constructed and arranged to normally maintain said groove above the plane of immersion of the float to 15 stop capillary flow of liquid upwardly on the wall of said float.

14. In combination, a tank, a liquid in the tank, a plurality of floats in the liquid forming a cover for the surface thereof, the combined cross sectional areas of said floats exceeding the exposed surface area of said liquid, and one of said floats having a depending portion of pyramidal form, the said float raised above and supported by the adjacent floats with the depending pyramidal 20 portion in engagement therewith to form a wedge forcing and maintaining the floats in cover forming relation over and substantially covering the surface of the liquid.

Dated this 2nd day of November, 1926.
BERNARD NEWMAN.
OLIVER WICKHAM.
